UNITED STATES PATENT OFFICE.

ALBERT L. CRAVER, OF LINWOOD, NORTH CAROLINA.

BRAKE.

No. 815,514.

Specification of Letters Patent.

Patented March 20, 1906.

Application filed December 12, 1905. Serial No. 291,446.

To all whom it may concern:

Be it known that I, ALBERT L. CRAVER, a citizen of the United States, residing at Linwood, in the county of Davidson and State of North Carolina, have invented certain new and useful Improvements in Brakes; and I do hereby declare the following to be a full, clear, and exact description of the invention, such as will enable others skilled in the art to which it appertains to make and use the same.

My invention relates to brake-operating mechanism for railway-cars; and its object is to provide means whereby the brakes may be manually applied by an operator when located either at the end of the car or at a point removed therefrom.

Another object is to provide simple means for locking the brakes after they have been applied, said means being adapted to be easily released, so as to free the brakes.

The invention consists of a rotatable rod, such as ordinarily employed upon the end of a car, said rod having a ratchet-wheel which is normally engaged by a gravity-operated locking-lever mounted on a car-roof. A combined hand wheel and gear is secured to the upper end of the rod and meshes with a smaller actuating-gear secured to a shaft, 25 which is mounted on and extends longitudinally of a car and has a hand-wheel whereby the same may be operated.

The invention also consists of the further novel features of construction and combination of parts.

In the accompanying drawings I have shown the preferred form of my invention.

In said drawings, Figure 1 is a side elevation of a portion of a car, showing my improved brake-operating mechanism mounted thereon. Fig. 2 is a plan view of the combined gear and hand wheel, and Fig. 3 is a detail view of the locking-lever and its bearing.

Referring to the figures by numerals of reference, 1 is a car, having a rotatable rod 2, mounted in brackets 3 on the end of the car, and secured to this rod is a ratchet-wheel 4, the teeth of which extend downward therefrom and are adapted to be engaged by one 45 end of a locking-lever 5, the other end of said lever being weighted, as shown at 6, whereby the lever is held normally in engagement with the ratchet-wheel. This lever is fulcrumed between ears 7, which extend upward from a

base-plate 8, adapted to be secured on the 55 roof 9 of a car.

Standards 10 are secured to the car-roof and constitute bearings for a horizontal shaft 11, having a hand-wheel 12 at one end, while a beveled gear 13 is secured to its other end 60 and meshes with a large gear 14, fastened to the upper end of the rod 2. Grips 15 radiate from the lower face of this gear 14, so that said gear can be utilized as a hand-wheel, if so desired. A rod 16 is secured to the standards 10 and serves to hold them rigidly connected, and this rod also extends to the end of the car and constitutes a bearing for the rod 2.

In using the mechanism herein described, 70 the rod 2 can be rotated so as to apply the brakes of the car either by manually turning the gear 14 or the wheel 12. It is obvious that wheel 12 is located at a point removed from the end of the car, so that the operator 75 will be subjected to practically no danger in applying the brakes, as it becomes unnecessary for him to go between or near the ends of the cars. However, should it be deemed necessary or desirable for the operator to apply the brakes while he is at the ends of the cars he can do so by turning the grips 15, and thereby rotating the gear 14. During the rotation of the rod 2 for applying the brakes the tee h of the ratchet-wheel 4 will 80 slip over the end of lever 5; but said end will prevent the wheel from rotating in the opposite direction and will therefore hold the rod, so as to prevent the brakes from being released. Should it be desirable to release the 90 brakes, the operator merely presses his foot under the weighted end of the lever and raises it, thereby freeing the ratchet-wheel. This mechanism can be very readily connected to any form of freight-car and will be found to 95 be very desirable.

What I claim is—

The combination with a car having standards thereon and a horizontal shaft mounted upon the standards and extending longitudinally of the car, said shaft having a hand-wheel at one end and a gear at its other end; of a brace-rod rigidly connecting the standards and projecting beyond one end of the car, a rotatable rod journaled within the 100 brace-rod, a gear secured at one end of the rotatable rod and meshing with the first-mentioned gear, grips radiating from the gear on 105

the rotatable rod and constituting a hand-wheel, a ratchet-wheel secured to the rotatable rod, and overlapping the top of the car, a bracket secured to the car-top, and a weight-
ed lever pivoted within the bracket and nor-
mally engaging and locking the ratchet-
wheel, said lever being adapted to be operated
by the foot.

In testimony whereof I have signed my
name to this specification in the presence of 10
two subscribing witnesses.

ALBERT L. CRAVER.
